UNITED STATES PATENT OFFICE

140,905

DESIGN FOR A MINIATURE CHAIR OR SIMILAR ARTICLE

Elliot Handler and Harold R. Matson,
Los Angeles, Calif.

Application January 13, 1945, Serial No. 117,408

Term of patent 3½ years

(Cl. D34—15)

To all whom it may concern:

Be it known that we, Elliot Handler and Harold R. Matson, both citizens of the United States, residing in Los Angeles, in the county of Los Angeles, State of California, have invented a new, original, and ornamental Design for a Miniature Chair or Similar Article, of which the following is a specification, reference being had to the accompanying drawing, forming a part thereof.

The drawing is a perspective view of a miniature chair showing our new design.

We claim:

The ornamental design for a miniature chair or similar article, as shown.

ELLIOT HANDLER.
HAROLD R. MATSON.
